GOBLET

Charles W. Carlson, Tiffin, Ohio

Application August 5, 1948, Serial No. 147,961

Term of patent 14 years

(Cl. D36—8)

To all whom it may concern:

Be it known that I, Charles W. Carlson, a citizen of the United States, residing at 235 Melmore Street, Tiffin, Ohio, have invented a new, original, and ornamental Design for a Goblet, of which the following is a specification, reference being had to the accompanying drawing, forming part thereof.

In the drawing:

Fig. 1 is a perspective view of the goblet, showing my new design; and

Fig. 2 is a horizontal cross-sectional view through the stem thereof, looking downward.

I claim:

The ornamental design for a goblet, as shown.
CHARLES. W. CARLSON.
